UNITED STATES PATENT OFFICE.

ANTHONY V. SANTARSIERO, OF NEW YORK, N. Y.

GAS HEATER.

Application filed February 10, 1923. Serial No. 618,383.

To all whom it may concern:

Be it known that I, ANTHONY V. SANTARSIERO, a citizen of the United States, residing at New York, in the county of New York and State of New York, have invented certain new and useful Improvements in Gas Heaters; and I do hereby declare the following to be a full, clear, and exact description of the invention, such as will enable others skilled in the art to which it appertains to make and use the same.

This invention has for its object to provide a portable gas heater of novel and attractive form, so constructed that it can be set upon a table or shelf off the floor. Gas heaters as heretofore constructed are primarily designed to stand on the floor and it not infrequently happens that persons walking on the floor will trip against the hose and thereby disconnect it from the burner. Not only are floor burners open to this objection but to the further objection that children like to tamper with them. Inasmuch as my invention is primarily designed to be supported on a table or shelf off the floor, the same is less likely to be tampered with by children and there is no danger of tripping over the same.

The invention also contemplates the provision of a gas heater so constructed that even if the same should be toppled over no particular damage would be done to the heater and the fire hazard is reduced to a minimum.

Another object of the invention is to provide a gas heater which may be swung in a horizontal plane so as to direct the heat to any desired point. It is a further object of the invention to provide a gas heater in which the body part thereof is made in sections so as to permit the heater to be packed in a small compass for storage or shipping and also to facilitate inspection of the burners.

The above and other novel features will appear from the detailed description taken in connection with the accompanying drawings which form a part of this specification.

In the drawings Fig. 1 is a side elevation of the gas heater;

Fig. 2 is a front elevation thereof;

Fig. 3 is a longitudinal section through the invention;

Fig. 4 is a transverse section through the

body of the heater to show the interior construction;

Fig. 5 is a horizontal section through the improved heater;

Fig. 6 is a fragmentary view showing the side sections as open;

Fig. 7 is a fragmentary view showing the front section as open and

Fig. 8 is a modified form of the invention showing a different form of refractory lining.

In the drawings, numeral 10 indicates a weighted support having a passageway therein through which gas may flow by way of the stopcock 11 and vertical tube 12. Telescoped over the tube 12 is a tube 13 having a seat for receiving a gasket *g* against which the upper end of the tube 12 may seat to form a gas-tight connection between the two tubes 12 and 13. The tube 13 extends from a **T** 14 which is plugged at one end as at 15 and at its other end is connected with a tube or pipe 16 which extends upward and is connected to the air chamber 17 of a burner 18. The burner is preferably provided with a circular series of holes 19 through which the gas passes.

The upper part of the **T** 14 constitutes a saddle 14' for supporting the main body of the heater. The outer casing of the heater is generally indicated by the letter B, and is held to the saddle 14' by a clamp block 14^a. Mounted on the clamp block is a spring clip 32, which will be subsequently further referred to. Bolts 14^b passing through the saddle and clamp block serve to clamp the lower section *b* of the casing B therebetween and also to hold the clip 32 in place. This body or casing is preferably divided into hinged sections the numeral 20 indicating one hinge and numeral 21 a second hinge, these hinges being affixed to a lower section *b* of the casing. Reference characters 20^a and 21^b indicate the side sections of the casing. The free ends of these sections are provided with aligned openings for receiving a removable locking pin 22 as will be readily understood from inspection of the various figures.

One end of the casing B is also provided with a hinged member 23 the hinge thereof being indicated at 24 which is also affixed to the section *b*. This hinged end has a circular opening and is adapted to be held in normal

position by means of the two hinged sections 20^a and 20^b, the same being provided with an inturned flange 25 behind which a circumferential edge of the end 23 is adapted to be received.

The other end of the casing B is closed by a plate or wall 26 which is preferably secured to the bottom section b of the body or casing by means of a removable pin 27. The 10 hinged sections 20^a and 21^b are provided with inturned flanges 28 behind which the peripheral edge of the wall or plate 26 may be received. The flanges 25 and 28 at either end of the sections 20^a and 20^b provide a neat 15 and solid joint with the members 23 and 26.

The end wall 26 is provided with an opening through which the reduced neck 17' of the air chamber 17 enters, the burner 18 being suitably attached to the end of the 20 neck and being disposed adjacent to the wall 26, it being spaced therefrom by suitable insulating material S such as asbestos.

Arranged and supported within the casing or body is a refractory shell R which at 25 one end has an opening corresponding to the opening at the end 23 of the casing B and at the other end has an opening which is adapted to receive the burner 18. The opening in the shell R into which the burner 30 enters is sufficiently large to leave an annular space between the burner and shell and this annular space is in connection with the atmosphere by means of a plurality of 35 passages 30 through which air will enter. It will be noted that the passages terminate 40 behind the row of holes 19 in the burner and consequently there is no danger of the flames passing out through said passages. Furthermore by reason of this arrangement air will 45 be drawn into the shell through these passages and the tendency will be for the heated air to leave by the open end of the refractory shell.

In order to permit easy lighting of the 45 gas burner there is provided a conduit 31 which extends through the shell R and side of the hinged body section and through this conduit a match or the like may be inserted to light the gas. This opening also 50 supplements the passages 30 through which air may enter the interior of the shell.

The refractory shell R is preferably supported in the spring-clip 32 which is secured to the saddle 14'. There is preferably provided a suitable insulating material between the refractory shell or lining R and the casing B, this insulating material being generally identified as S throughout the several views. The refractory lining or shell is 55 preferably a baked clay product, so that after same has once become heated it will maintain its heated condition for a considerable period of time and will allow a less quantity of gas to be used to keep the said 60 lining or shell in a heated condition.

While I prefer that the refractory shell or lining R shall be a clay product it is within the spirit of the invention to make the same of other material such as a metal shell lined on its interior with asbestos or 70 other fire resisting material. Fig. 8 shows this form of the invention and 35 indicates the metal shell and 36 the interior lining thereof. Instead of providing an annular space between the burner and adjacent end 75 of the metal shell, the shell may snugly telescope the latter. The equivalent of the annular space may be obtained by causing the shell to flare upwardly behind the openings 19 in the burner and this upward flare 80 may be connected with passages 30^a leading to the atmosphere.

When it is desired to disassemble the invention for storing or shipment it is merely necessary to remove the various pins which hold the sections of the casing in place and the other parts can then be removed and readily packed. The base part of the heater is readily separable from the upper part 85 thereof by reason of the telescopic connection 90 12 and 13.

The specification sets forth the main features of the invention but it will be readily apparent to those skilled in the art that the 95 details of the structure may be widely varied without departing from the substance or real essence of the invention.

What I claim is:

1. In a gas heater, the combination of a 100 burner, a cylindrical casing into one end of which the burner enters, said casing being divided into sections, one of said sections being swingable on a pivot extending transversely to the axis of said body and the other sections being swingable on axes parallel to the axis of said casing.

2. In a gas heater, the combination with a support, of a horizontally disposed cylindrical casing turnably mounted for movement in a horizontal plane, and a gas conduit leading from one end of the casing to the said support.

3. In a gas heater, the combination with a cylindrical casing, of an external radial tube 115 affixed thereto and turnably mounted on a support, a pipe in connection with said tube and terminating adjacent one end of the casing, and a burner within the casing and in connection with one end of the pipe.

4. In a gas heater, the combination of a saddle having a spring-clip, a cylindrical shell seated in said spring-clip, a burner at one end of said shell and the other end of the shell being open, a casing for said shell including a pair of segmental sections hinged to either side of the saddle and means for holding said sections in closed position about the said shell.

5. In a gas heater, the combination of a saddle, a horizontally disposed cylindri- 130

cal shell seated thereby, a tube affixed to the saddle and extending radially with respect to said shell, a pipe in connection with said tube leading toward one end of the shell, 5 and a burner within the shell and in connection with the pipe.

6. In a gas heater, a saddle having a downwardly projecting tube, a pipe in connection with the tube and extending horizontally therefrom for a distance and then 10 bent upwardly, a horizontally disposed gas burner at one end of the pipe, a cylindrical

shell into which the burner extends, said body having an open mouth through which the heat from the burner may be projected, 15 a casing within which the said shell is enclosed, and means on the saddle for supporting the said casing.

7. The combination as specified in claim 6, said casing consisting of a plurality of members hinged at their lower ends so as to open outwardly when desired.

In testimony whereof I affix my signature.

ANTHONY V. SANTARSIERO.
